G. HUGUENIN

MEANS FOR BANDING PACKING CASES

Filed Oct. 19, 1922

UNITED STATES PATENT OFFICE.

GUSTAV HUGUENIN, OF CHAM, SWITZERLAND, ASSIGNOR TO NESTLE AND ANGLO-SWISS CONDENSED MILK COMPANY, OF CHAM, SWITZERLAND, A CORPORATION OF SWITZERLAND.

MEANS FOR BANDING PACKING CASES.

Application filed October 19, 1922. Serial No. 595,690.

To all whom it may concern:

Be it known that I, GUSTAV HUGUENIN, a citizen of the Republic of Switzerland, residing at Cham, Switzerland, have invented certain new and useful Improvements in Means for Banding Packing Cases, of which the following is a full, clear, and exact description.

This invention relates to means for producing and applying endless binding hoops or bands applicable generally where such bindings are employed but more particularly intended for use in connection with packing cases of the kind in which merchandise such as condensed milk is contained for the purpose of transport.

The present invention has for its object to provide a device which is adapted to sever a strip of material of definite length supplied from a roll or the like and to lay or apply the same about a case, container or other object in a predetermined position and in a condition of tautness and to join the ends of the strip, which are caused to overlap, by welding the same together so that an endless welded hoop or band results whereof the surface is smooth and flat there being no apparent ridge or projection at the aforesaid point of junction and the tension of the band is preserved.

According to this invention the device comprises a table adapted to receive and hold the case, container or other object in a predetermined or definite position and to be straddled by a length of binding strip which is fed into and along a groove or recess formed in the surface of the table. The material or strip is contained in a roll mounted adjacent to one side of the table and when a predetermined length has been fed or drawn from the roll the said length is severed by a suitable cutting device or guillotine. The severed strip is then manipulated by means of a kind of folding frame consisting of hinged arms so as to bend portions of the same against the sides of the case or other object and similarly the ends of the strip are bent over and upon the upper surface of the case or other object so as to overlap each other. The welding of the said ends is then effected the lapped extremities of the encircling strip being inserted

between electrodes in such a manner that they rest one above the other in a flat condition and are held in that position by clamping devices with the result that a flat portion is presented for welding which latter operation is thereby performed without unduly heating the binding strip at any other portion thereof. The clamping devices prevent any slackening of the strip during the operation of welding.

By these means the pre-determined position of the binding is preserved and its application effected without destroying the tautness and close adherence thereof about and to the case or other object.

In order that the invention may be readily understood and carried into effect, same will now be more fully described with reference to the accompanying drawings, in which:

Figures 1, 2 and 3 are diagrammatic views illustrating the successive operations of binding the strip about the case or other object to be bound.

Figures 4 and 5 are also diagrammatic views in front elevation and plan respectively of the improved device drawn to a larger scale.

Referring first to Figures 1 to 3 inclusive the material from which the hoop or band is formed is drawn from a roll A suitably mounted for rotation and the length a drawn therefrom is extended over a supporting table B which is grooved or recessed for its reception. Having obtained the length required which is represented by the distance between the adjustable stop C and the cutting device D the latter is operated to effect the severance of the said length from the stock contained in the roll A. The box, case or other object E having been placed and positioned upon the table B the length of material is bent upwards along the sides of the object by turning the arms F F about their pivots f f and then by similarly turning the arm extensions F' F' about their pivots f' f' in the arms F F the ends of the said length of material are bent and brought over the top of the object the length of material being sufficient to allow a lapping of the said ends one upon the other. In Figure 1 the box or object E is shown in position with the length of strip beneath the same and extending at either side there-

of, i. e., from the cutter D at the left-hand side to the adjustable stop C at the right-hand side. If reference be now had to Figure 2 the first stage in the binding of the strip will be observed by reason of the deflection or turning of the hinged arms F F and the further bending of the strip so as to form a lapped joint is readily observable in Figure 3.

10 The box or object is positioned on the table B by a block b which may be adjustable so as to admit of the band being applied at any desired distance from the side of the box or object and the table is also provided with a bracket b¹ which is adapted to co-act with the aforesaid block in holding the box or object in the desired position on the table during the application of the binding strip. The strip may be held in the 15 groove or recess b^x in the table B by means of lateral trigger springs or by magnets indicated at a¹.

The arm extensions F¹ F¹ may each carry a trigger lever f² f² adapted to take a bearing upon the strip see Figure 3 and to permit of the parts E¹ E¹ being turned up out of contact with the top of the box or object.

Assuming the box case or other object to be in position on the table B with a suitable 20 length of strip in the groove or recess B^x (Figures 4 and 5) and the said strip bent about the box or object as above described the clamping levers G G are operated by means of the handle g and right and left 25 screw threaded spindle g¹ so as to grip the said strip and force the ends of the latter into close contact the one upon the other between the electrodes H H¹. By means of the handle or grip h¹ the electrode H¹ is 30 pressed into firm contact with the ends of the binding strip whereupon electrical contact is established in the primary line I of an alternating current transformer. At this moment a current of high intensity and low 35 voltage flows through the secondary K which is carried through the ends of the binding strip from the electrode H¹ to the electrode H and thereby the ends of the binding strip 40 are immediately welded together over a broad surface. By now reversing the movement of the handle g the clamping devices G G are released from holding engagement 45 with the strip and the case or object having a complete hoop or binding applied thereto 50 may be removed.

Devices for butt welding wire bindings on boxes or containers are known in which the current is conducted through clamps but certain disadvantages arise in practice owing 55 to a part of the current flowing through the binding and passing out ineffectively as regards any assistance to the welding operation. The binding moreover becomes heated and the container suffers burning while the 60 tension of the binding also suffers and when

the latter cools upon the completion of the welding a shortening thereof takes place and not infrequently rupture ensues.

By the use of separate electrodes H H¹ which conduct the current directly to the flat lapped extremities of the strip these objections are obviated or minimized and the binding is preserved in a taut condition the operation being conducted without risk of the binding becoming heated otherwise than at the point of welding.

I claim:—

1. Apparatus for applying binding hoops or bands to packing cases, comprising in combination a table adapted to hold the case in predetermined position, a groove in said table for receiving the binding strip and positioning the latter beneath the case, a mounting for a roll of said strip, an abutting stop for said strip as same is fed from said roll, and a cutting device for securing the fed strip from the roll; a folding frame mounted on the table and consisting of hinged arms adapted by manipulation to bend portions of the cut strip against the sides of the case and other portions of the strip on the top of the said case with the latter portions lapping the one over the other; a welding means consisting of separate electrodes adapted to conduct the current directly to the flat lapped extremities of the binding strip, and clamping devices for holding the said lapped extremities in position while being subjected to the welding operation.

2. Apparatus for applying binding hoops or bands to packing cases, comprising in combination a table, a block thereon adapted to hold and position the case, a roll mounted for rotation in suitable relation to said table, a groove in the table for the reception of the length of material drawn from said roll, an abutting stop for determining said length and a cutting device for separating the length from the roll, laterally disposed arms pivotally mounted on the table, arm extensions pivotally connected with the first mentioned arms and trigger levers adapted to take a bearing upon the portions of the strip lying on the top of the case, clamping levers for gripping and contacting the over-lapping ends of the strip, a handle for operating the said gripping levers, a pair of electrodes disposed respectively above and below the aforesaid over-lapped portions, a depressing handle for the upper electrode, and means for supplying current to said electrodes for effecting the welding of the lapped ends of the strip which constitutes the binding hoop or band.

3. Apparatus for applying binding hoops or bands to packing cases, comprising in combination a table, a block and a bracket associated with said table for holding the case in position on the table, a groove in the table, a gauging stop adjacent one end of the

- table, a cutting device adjacent the other end of the table and a mounting for a rotatable roll of binding material near the cutting device, the arrangement being such that
- 5 a predetermined length of said material is cut from the roll and occupies the said groove in a position in which it straddles the under side of the case held on the table, laterally disposed arms pivotally mounted on
  - 10 the table, arm extensions pivotally connected with said laterally disposed arms and trigger levers adapted to bear on the portions of the strip lying in superposed or over-lapping relation on the top of the case,
  - 15 clamping levers for gripping and contacting the over-lapping portions of the strip, screw spindles associated with said levers and an operating handle for said spindles, a pair of electrodes disposed the one above and the other beneath the aforesaid lapped portions 20 of the strip, a depressing handle in operative relation to the upper electrode and means for supplying current to said electrodes for effecting the welding of the lapped ends of the strip which thereupon constitutes an endless binding hoop or band whereof the junction point is smooth and flat and the tension maintained.

In witness whereof I have hereunto subscribed my signature, 30 Sept., 1922.

GUSTAV HUGUENIN.
